B. F. GARDNER.

SYSTEM FOR REMOVING OBSTRUCTIONS TO THE FLOW OF FLUID IN THE
EARTH STRATA ADJACENT TO WELLS.

APPLICATION FILED JULY 1, 1920.

UNITED STATES PATENT OFFICE.

BENJAMIN FULTON GARDNER, OF CHICAGO, ILLINOIS.

SYSTEM FOR REMOVING OBSTRUCTIONS TO THE FLOW OF FLUID IN THE EARTH STRATA ADJACENT TO WELLS.

1,372,743.

Specification of Letters Patent. Patented Mar. 29, 1921.

Application filed July 1, 1920. Serial No. 393,436.

To all whom it may concern:

Be it known that I, BENJAMIN FULTON GARDNER, a citizen of the United States, residing at 4315 Drexel Boulevard, Chicago, 5 in the county of Cook and State of Illinois, have invented a certain new and useful Improvement in Systems for Removing Obstructions to the Flow of Fluid in the Earth Strata Adjacent to Wells, of which the following is a full, clear, concise, and exact 10 description, reference being had to the accompanying drawings, forming a part of this specification.

My invention relates to improvements in 15 a system for removing obstructions to the flow of fluids in earth strata, and my object is to provide means by which an electric current of relatively high voltage can be maintained in a predetermined oil, gas, sulfur or 20 other mineral bearing strata for the purpose of producing electrical effects therein.

There are inventions for which patents have been granted for methods, systems and devices for removing the obstructions to the 25 flow of oil in oil wells. Where heat has been employed to liquefy the paraffin, asphaltum or other gummy residue of petroleum, it merely resulted in cleansing the bore of the well and the inclosing rock for a distance 30 limited to the heat generating capacity of a heater adapted to enter the bore of a well and to be submerged in cooling fluids. Primarily the object of my invention is to accomplish all that it was possible to do by 35 the old methods and by an enlarged system to comprise a plurality of wells in one operation; to electrically heat and produce other electrical effects—the expansion of gas—in the territory between and adjacent to oil and 40 gas wells.

The invention will be fully understood 45 from the following specification taken in connection with the accompanying drawing which represents diagrammatically a system for removing obstructions to the flow of fluid in the earth strata designed in accordance with the invention.

Referring to the drawing A, designates 50 the bore of a well, as for example an oil or gas well, *a*, the casing and *a'* the tubing or mine pipe of a well. B designates the bore of an adjacent well, *b* the casing and *b'* the tubing of said adjacent well. C designates 55 a source of relatively high potential such as an electric dynamo. The circuit *per se*, is

designated by *c*, from the positive side of brush of the dynamo to the well and thence, as illustrated by a dotted line, to the grounded heater-electrode, D, located at the bottom of the well. The circuit from well A 60 through the earth strata to the adjacent well B is indicated by arrows and connected to the grounded electrode D', from said electrode through the insulated circuit *c'* to the negative brush of the dynamo or other 65 source of potential.

It will be observed the two wells and the strata between them are electrically connected in series.

The operation of my improved system for 70 removing obstructions to the flow of fluids in earth strata is as follows:

An electric current of sufficient voltage to overcome whatever resistance there may be in the circuit described to maintain a watt 75 output power, to increase the temperature at the bottom of said well and in the strata between said wells to a degree sufficient to liquefy paraffin, asphaltum and other obstructing residue of petroleum and to increase the gas pressure by heat, thereby forcing or blowing movable detritus from out the interstices and crevices of the rock adjacent to said wells.

The wire circuits from the source of potential or dynamo to the grounded electrode D, is insulated for a high potential and threaded through the tubing or mine pipe to the electrodes grounded to the metal tubing, which is likewise grounded by the fluid and 80 earth. If desirable, resistor elements may be in circuit and connected to the grounded electrodes. As the electric current passes through and from the metal tubing of the initial well to and through the tubing of the 85 adjacent well, it is essential to use alternating electric current as direct current would produce electrolysis in iron tubing and in time puncture it, causing leakage.

Oil is a dielectric of high efficiency and used 100 for insulating currents of high potential but water and salt water are conducting fluids and universally found at the bottom of deep wells of the character described. Water is decomposed and is easily heated to the boiling point by conducting an electric current 105 through the fluid. The water at a temperature of 212° F., will impart sufficient heat to the superimposed strata to melt paraffin, etc. Gas is likewise a conductor of electricity but 110

of high resistance. The heating effect of my improved system will cause the gas to expand and as a result the well will "blow". This effect I have heretofore produced with 5 other methods of heating wells with electricity and for which I was granted patents.

While I have described in considerable detail one specific embodiment of my invention, it will be understood that this is illustrative only, and for the purpose of making the invention more clear, and that I do not regard the invention as limited to these details, nor any of them, except in so far as such limitations are included within the 10 terms of the accompanying claims in which it is my intention to claim all novelty inherent in my invention as broadly as is permissible in view of the prior art.

What I claim is:

20 1. In a system of the class described means for liquefying paraffin and similar gummy residue in oil bearing strata, said means comprising electrodes located within the tubing of a plurality of oil wells, and means to connect said electrodes in series whereby electric current will be caused to pass from one well to adjacent wells.

25 2. In a system of the class described electrodes within the bore and at the bottom of the tubing in a plurality of oil wells said electrodes grounded to said tubing and said tubing grounded to the earth and means whereby electric current is caused to pass from one electrode to another thereby reducing 30 obstructions to the flow of fluid into said wells.

35 3. In a system of the class described, electrodes comprising resistor parts, within and grounded to the bottom of tubing submerged in fluid at the bottom of oil wells, and means to electrically unite said electrodes within said wells in series whereby heat may be gen-

erated to liquefy indurated matter removing obstructing deposits to the flow of fluid into said wells.

4. In a system of the class described means to generate gas pressure by expanding the gas in an oil bearing strata whereby the said generated pressure will remove obstructing matter to the flow of fluid to wells in said oil bearing strata, said means comprising combined heater-electrodes located at the bottom of said wells and means to simultaneously maintain an electric current in a series of said heater-electrodes in a plurality of wells.

5. In a system of the class described means to increase the temperature of water under oil bearing strata, thereby imparting a liquefying heat to the indurated products of petroleum in the superimposed oil bearing strata, said means comprising a source of electrical potential, circuits and submerged electrodes located in different wells.

6. In a system of the class described means to impart heat to oil bearing strata whereby the gas therein is expanded creating a force to dislodge and liquefy the obstructing residue of petroleum, said means comprising a source of electric energy, circuits, submerged electrodes adapted to enter the bore of oil well tubing and be lowered to the bottom of said tubing and means to ground said electrodes to said tubing, which is also grounded to the earth as by water surrounding said tubing or by the bottom end of said tubing resting upon the earth, a plurality of said electrodes in electrical connection distributed among a plurality of wells.

In witness whereof, I hereunto subscribe my name this 24th day of June, A. D. 1920.

BENJAMIN FULTON GARDNER.
